UNITED STATES PATENT OFFICE.

ERNST OSCAR NEBEL, OF PHILADELPHIA, PENNSYLVANIA.

DESIGN FOR STOCKING.

Application filed March 3, 1928. Serial No. 25,660. Term of patent 14 years.

To all whom it may concern:

Be it known that I, ERNST OSCAR NEBEL, a citizen of the United States, residing at Philadelphia, in the county of Philadelphia and State of Pennsylvania, have invented a new, original, and ornamental Design for Stockings, of which the following is a specification, reference being had to the accompanying drawing, forming part thereof.

Figure 1 is a rear elevation of a stocking in position of use showing my design, Figure 2 is a side elevation of the stocking flat, and Figure 3 shows in enlarged detail the design of the upper part of the heel and high splice illustrated in Figures 1 and 2.

I claim:

The ornamental design for stocking, as shown.

ERNST OSCAR NEBEL.
